OILER FOR AIR TOOLS

Ottmar A. Kehle, West Los Angeles, Calif., assignor, by mesne assignments, to Sterling Tool Products Company

Application May 20, 1939, Serial No. 274,747

3 Claims. (Cl. 184—55)

My invention has to do with improvements in oilers and, more particularly, relates to oilers for interposition in air lines for automatically lubricating air operated devices.

6 This application is a continuation in part of my copending application Serial Number 73,283, filed April 8, 1936, issued as Patent No. 2,187,241, entitled Oiler for air tools.

10 My experience in the art has been that prior oilers are impracticable and often totally inoperative to deliver oil to the air line when the velocities or pressures are materially reduced. That has been due largely to the lack of a design and structure capable of providing any dependable pressure differential between the oiler reservoir and the outlet orifice. I have found also that, at relatively high velocities, the prior art devices are unsatisfactory, inefficient and not at all dependable. For instance, in the operation 15 of ordinary air tools such as sanding and buffering devices driven by air motors, the usual desirable rate of oil feed is about one-eighthieth of a pint per hour and one of the principal shortcomings of prior art oilers has been that if they are so 20 designed and constructed as to provide such a measured flow at extremely high velocities, they are incapable of delivering any oil at relatively low velocities or, conversely, if capable of delivering oil at extremely low velocities, they deliver 25 too much oil at high velocities. Also, I have found prior art devices require pulsations in the air line for their operation and are of such design and structure that the oil passageways become 30 clogged with foreign matter in the oil.

35 It is therefore among the aims and attainments of my invention to cure those shortcomings by providing an oiler which is capable of efficient and dependable operation under all working conditions and at varying pressures and velocities; which does not require pulsations in the air line for its operation; which is extremely simple in structure, durable and economical of manufacture and in which the amount of oil delivered into the air line may be predetermined and controlled.

40 Another object is the provision of simple, novel and efficient means for controlling the oil delivery independently of the velocity and pressure in the air line.

45 Still another object is the provision of a device capable of maintaining an efficient pressure differential between the oil reservoir and the outlet orifice under all working conditions.

50 How my invention accomplishes those as well 55 as other objects will become obvious from the

following description of one presently preferred adaptation, for which purpose I shall refer to the accompanying drawing, in which:

Fig. 1 is a plan view partly in section;

Fig. 2 is a vertical section on line 2—2 of Fig. 5 1; and

Fig. 3 is a fragmentary vertical section showing a variational form.

Referring now to the drawing, I show at 5 a container providing an oil reservoir 6. The bottom wall 7 of the container has an integrally formed tubular member 8 projecting upwardly from its inner central portion, which tubular member is provided with interior threads 9. Bottom wall 7 is also provided with an upwardly 10 extending annular flange 10 forming a cup into which the bottom end of side wall 11 fits, there being interposed between the bottom end of wall 11 and the top face of wall 7 a suitable gasket 12. Side wall 11 is preferably made of some 15 transparent material such, for instance, as glass, to afford visibility of the contents of the reservoir. A head 15 has a depending annular flange 17 which provides a socket into which the top 20 end of side wall 11 fits, there being interposed between the upper end of wall 11 and the bottom surface of head 15 a suitable gasket 18. A stud 19, having a threaded lower end 19a, is formed integrally with and projects downwardly from 25 the head, the threaded portion 19a threadededly engaging the tubular member 8, so that in assembling the device it is only necessary to rotate the head and container members relative to each other until side wall 11 is drawn against the 30 gaskets 10, 18 to form a fluid tight seal. 35

Extending transversely through head 15 is an air passageway 20 which has between its inlet end 21 and its outlet end 22 a somewhat elongated portion 23 of reduced diameter. An opening 30 extends through the bottom of passageway 20 and communicates with the reservoir 6. 40

An opening 35 extends through the top wall of the head 15 into the passageway 20 and a concentric opening 36 extends through the bottom wall of the head from the passageway to communicate with the reservoir. In the passageway formed by openings 35 and 36, I mount a tube 40 whose upper portion 41 fits opening 36 in fluid tight engagement therewith. A plug 44 50 closes the top end of opening 35, and between the under face of its head and the top surface of head 15, I provide a gasket 45.

The lower end of tube 40 is tapered and threaded at 47 and slotted at 48, and over its 55

tapered end I threadedly mount a tapered and interiorly threaded sleeve 49 for the purposes to be described.

Through that portion of the side wall of tube 40 which is opposite the direction of flow of air through passageway 20 and which is central of the passageway 20, I provide a small outlet orifice 59 and mounted longitudinally in tube 40 is a capillary member here shown as a wick 55 whose bottom end projects from tube 40 and hangs therefrom submerged in the oil in the reservoir 6. The lower end of tube 40 is also submerged in the liquid in the reservoir. Wick 55 extends upwardly within tube 40 to a point preferably spaced above the outlet orifice 59.

A filling port 60, closed by headed screw 61, is provided through head 15 and communicates with the reservoir for purposes of filling the reservoir.

Head 15 is internally threaded at the ends 21 and 22 of passageway 20 for connection to an air line.

In operation, the air under pressure passes from right to left through passageway 20, creating pressure on the fluid in the reservoir through opening 30, and inasmuch as the air stream is divided by the tube 40, which extends entirely across the passageway, the divisions of the air stream converge at a point around the orifices 59, inducing a vacuum at the outlet orifice which acts to draw oil from the closely adjacent wick portion within the tube-wick 55 extending from the oil reservoir to a point preferably spaced above the orifice. The reduced portion 23 of the passageway 20, which is traversed by tube 50, increases the velocity of air moving around the tube to materially reduce the pressure at outlet orifice 59 even at extremely low pressures. The pressure differential between the reservoir and the outlet orifice is further increased by the fact that the opening 30 is between the inlet end 21 and the restricted portion 23 and by virtue of the fact that the cross sectional area of opening 30 is relatively greater than that of the outlet orifice. The oil withdrawn through orifice 59 enters the center of the air stream and thus becomes intimately admixed with the air and is not thrown against the inner walls of the passageway.

The oil flow through wick 55 may be varied by the relative degree of constriction applied to the submerged end of the wick by means of screwing or unscrewing sleeve 49 with relation to the lower, threaded end of tube 40.

In Fig. 3, I show a variational form of flow regulating device for my oiler. In that view, head 15, passageway 20 and restricted passageway portion 23 are the same as before described. However, in this variational form the tube 40a is provided with a longitudinal slot 68 at its upper end and bolt 61 is hollow at its lower end to provide a sleeve portion 62 which is slidable longitudinally over the slotted end of tube 40a

(by means of screwing bolt 61 in or out of threaded opening 65 through the top of the head) to vary the length of that portion of slot 68 which is in communication with passageway 20.

In the foregoing description, I have resorted to considerable details of structure and association of parts for the purpose of making my invention clearly understandable. I wish it understood, however, that it may be modified within its broader scope as defined by the appended claims. 10

I claim:

1. An oiling device for interposition in an air line, comprising: a casing provided with an air passageway therethrough and an oil reservoir therein, said passageway having a portion of reduced diameter between its ends, a tubular member extending transversely through said air passageway at a point between and spaced from the ends of the said reduced diameter portion, an unobstructed inlet opening in the casing establishing communication between the air passageway and reservoir, said inlet opening being positioned at a point between said reduced diameter portion and the inlet end of the air passageway, an outlet orifice in the tube, said orifice having a cross-sectional area smaller than that of said inlet opening and communicating with the passageway only at a point facing the outlet end thereof, and a wick in and extending longitudinally of the tube from the reservoir to a point opposite the outlet orifice. 20

2. An oiling device for interposition in an air line, comprising: a casing provided with an air passageway therethrough and an oil reservoir therein, said passageway having an elongated portion of reduced diameter between its ends, a tubular member extending transversely through said air passageway at a point between and spaced from the ends of the said reduced diameter portion, an inlet opening in the casing establishing communication between the air passageway and reservoir, said inlet opening being positioned at a point between said reduced diameter portion and the inlet end of the air passageway, an outlet orifice in the tube, said orifice having a cross-sectional area smaller than that of said inlet opening and communicating with the passageway only at a point substantially centrally thereof and facing the outlet end thereof, and a wick member in and extending lengthwise of said tube 50 from the reservoir to a point opposite the outlet orifice. 45

3. An oiler for use in an air line, comprising: a body having an oil reservoir and an air passageway, a tube extending transversely of the passageway and into the reservoir, said tube having an opening communicating with the passageway, a wick mounted longitudinally in the tube, the end portion of the tube within the reservoir being tapered, exteriorly threaded and slotted, and a tapered collar threadedly mounted over said end of the tube. 55
